UNITED STATES PATENT OFFICE.

LEOPOLD KABIS, OF CHEYENNE, WYOMING, ADMINISTRATOR OF THOMAS MOORE, DECEASED.

DESIGN FOR A PACK-SADDLE FRAME.

SPECIFICATION forming part of Design No. 29,298, dated August 30, 1898.

Application filed July 27, 1898. Serial No. 687,049. Term of patent 14 years.

To all whom it may concern:

Be it known that THOMAS MOORE, deceased, late a citizen of the United States, and a resident of Cheyenne, county of Laramie, and State of Wyoming, duly invented and produced a new and original Design for Pack-Saddle Frames, of which the following is a full, clear, and exact description, reference being had to the accompanying drawings, forming a part hereof.

Figure 1 is a plan view of a pack-saddle frame embodying the new design. Fig. 2 is an end elevation of the frame seen in Fig. 1.

As shown in the drawings, the leading and material feature of the design consists of a pair of flat bodies 1, having irregular outlines with curved forward and rear ends, the centers of said bodies 1 being in the form of

oppositely-arranged irregular curves, and extending upwardly from the forward and rear ends of the pair of bodies are the semicircular slotted arches 2. The top faces of the end portions of the bodies 1 are flat, and the curved central portions are given a slight downward curve.

What is claimed is—

The design for a pack-saddle frame, substantially as herein shown and described.

In testimony whereof I affix my signature in presence of two witnesses.

LEOPOLD KABIS,
Administrator of Thomas Moore, deceased.

Witnesses:

WALTER R. STOLL,
Wm. R. SCHNITGER.
